US0D1019922S

(12) United States Design Patent (10) Patent No.: US D1,019,922 S
(45) Date of Patent:  Mar. 26, 2024

(54) WALL HOLDER FOR SHOWER STEAMERS

(71) Applicant: Kongxie Huang, Fuzhou (CN)

(72) Inventor: Kongxie Huang, Fuzhou (CN)

() Term: 15 Years

(21) Appl. No.: 35/517,873

(22) Filed: Jun. 26, 2023

(80) Hague Agreement Data

Int. Filing Date: Jun. 26, 2023

Int. Reg. No.: DM/230279

Int. Reg. Date: Jun. 26, 2023

Int. Reg. Pub. Date: Jul. 21, 2023

(51) LOC (14) Cl. 23-04

(52) U.S. Cl.

USPC D23/366; D23/208

(58) Field of Classification Search

USPC D23/207, 208, 355, 360, 361, 362, 363, D23/366, 367, 386, 387, 388

CPC ... A61L 9/015; A61L 9/04; A61L 9/12; A61L 9/13; A61L 9/15
